UNITED STATES PATENT OFFICE.

ADOLPH LEEFEBVRE, OF ST. CATHARINES, ONTARIO, CANADA.

GARMENT SUSPENDERS.

Application filed May 2, 1925. Serial No. 27,600.

To all whom it may concern:

- Be it known that ADOLPH LEEFEBVRE, a subject of the King of Great Britain, residing at No. 2 Center Street, in the city of 5 St. Catharines, in the county of Lincoln and Province of Ontario, Canada, has invented certain new and useful Improvements in Garment Suspenders, of which the following is a specification.
- 10 My invention relates to improvements in garment supporters and more particularly to trousers suspenders and in the disclosure herein made the latter is described as an example.
- 15 Trousers suspenders are usually made of elastic fabric and rubber shoulder straps and these elastic straps in a comparatively short time lose their elasticity by the rubber going "dead" and consequently become a discomfort 20 to the wearer long before the suspenders are actually worn out. Various spring devices have been substituted for the elastic rubber, but these have failed in their purpose owing to lack of sufficient elasticity.
- 25 The first important object of this invention is to provide in a trousers suspender comprising shoulder straps spring means interposed between sections of the straps which will afford the proper degree of elasticity 30 and also retain their elastic properties so long as the suspenders wear.
- A second important object is to provide a device of the class specified which will be simple and inexpensive to manufacture.
- 35 These, together with other objects, may be attained by the construction, combination, and arrangement of parts as will be hereinafter more fully described, illustrated in the accompanying drawing, and pointed out 40 in the claim hereunto annexed.
- Referring to the drawing:
- Figure 1 is a view of suspenders constructed in accordance with this invention;
- 45 Figure 2 is an enlarged view of the spring portion in normal position;
- Figure 3 is a similar view showing the suspender strap expanded;
- Figure 4 is a sectional side elevation of the spring portion;
- 50 Figure 5 is a sectional front elevation of the spring portion; and,
- Figure 6 is a detailed magnified sectional view of the union of two strap sections.
- 55 Similar reference characters refer to similar parts throughout the several views.
- This invention includes a pair of non-
- elastic main shoulder straps, indicated by the numeral 10, crossed as usual at the back and stitched or otherwise suitably united as indicated at 11. 60
- At both the forward end and the rear end of each of these main straps are similar short straps 12. Both the main straps and the short straps are folded on themselves and stitched or otherwise suitably secured as at 65 13 to form loops or envelopes, the bent portion of the short strap being adapted to face or meet the bent portion of the main strap. In the bends of these straps are spaced holes protected by the eyelets or bushings 70 14, the eyelets in the main strap registering with those in the short strap, and at the opposite or low end of the short straps is a loop in which it held the usual link 15 of the garment supporting member 16. 75
- The main shoulder straps 10 are connected to the short straps 12 by endless cords 17 woven through the eyelets 14 and looped within the said envelopes. 80
- Spiral springs 19 are coiled around the said cord where it is looped within the said envelopes, and these springs keep the cord taut and thereby keep the main strap and the short strap normally in contiguous relation as shown in all the figures except Figure 3 which shows the two straps stretched apart under a pull or strain as would be caused by the flexing of the body of the wearer. When a strain is thus applied to the suspenders the gap between the main 90 strap and short strap widens and the cord 17 is pulled partially through the eyelets 14, and when the maximum yield is reached, the springs 19 are compressed so that no further cord can be pulled out of the envelopes. When the strain is released the springs return the main strap and short strap to contiguity by expanding and taking up the cord. 95
- There has thus been produced a simple 100 and efficient device of the class described and for the purpose specified, and now having fully disclosed my invention and the manner in which it is ascertained, what I claim and desire to secure by Letters Patent is:—
- In a garment supporter, a flexible non-elastic shoulder strap having an envelope formed by folding the end of the shoulder strap on itself, said envelope having a pair 110 of spaced openings in the bend thereof, a short flexible non-elastic strap having means

on one end to which a garment connecting member is secured, an envelope formed thereon, the latter envelope having a pair of spaced openings in the bend thereof, the 5 bends in both envelopes being normally contiguous and the openings therein adapted to register, an endless cord having rounded ends and normally straight parallel intermediate sections, said intermediate sections 10 being passed through said openings and

adapted to slide therethrough and the rounded ends occupying the respective envelopes, and spiral springs coiled around the portions of the cord within the envelopes and confined therein by their ends abutting 15 against the edges of said openings.

In testimony whereof I have affixed my signature.

ADOLPH LEFEBVRE.
